[57] CLAIM

The ornamental design for an automobile body, as shown and described.

DESCRIPTION

FIG. 1 is a front perspective view of an automobile body showing our new design.

FIG. 2 is a rear perspective view thereof; and,

FIG. 3 is a left side view thereof, it being understood that the opposite side to that shown is a substantial mirror image.

It will be understood that there is no claim being made to the wheels and tires shown throughout the drawings in phantom.
